SAFETY RAZOR CASE

Martin Glaberson, Ardsley, N.Y., assignor to Eversharp,
Inc., Milford, Conn., a corporation of Delaware

Filed Dec. 23, 1964, Ser. No. 83,130

Term of patent 14 years

(Cl. D58—12)

FIG. 1 is a plan view of a safety razor case embodying my new design;

FIG. 2 is a front elevation thereof;

FIG. 3 is a rear elevation thereof; and

FIG. 4 is an end view thereof.

I claim:

The ornamental design for a safety razor case, as shown.
